UNITED STATES PATENT OFFICE.

HECTOR MACFARLANE AND NORMAN EVERARD ROGERS, OF LONDON, ENGLAND,
ASSIGNORS TO BODDY LIFESAVING APPLIANCES (1914) LIMITED, OF LONDON,
ENGLAND.

LIFE-SAVING APPLIANCE.

1,179,018.

Specification of Letters Patent. Patented Apr. 11, 1916.

Application filed May 6, 1915. Serial No. 26,292.

To all whom it may concern:

Be it known that we, HECTOR MACFARLANE and NORMAN EVERARD ROGERS, subjects of the King of Great Britain and Ireland, residing at 2 Broad Street Place, London, England, have invented certain new and useful Improvements in Life-Saving Appliances; and we do hereby declare the following to be a full, clear, and exact description 5 of the invention, such as will enable others skilled in the art to which it appertains to make and use the same.

This invention relates to life-saving waistcoats, swimming appliances and the like, and has for its object to provide a device which is simple and cheap of construction and efficient in use, which can be quickly secured upon a wearer and which can be so adjusted that a standard size of 10 device can be used for persons of various ages and sizes.

The device may be constructed upon the principle set forth in British specification No. 13475/1912 whereby a person wearing 15 the device will automatically assume a rearwardly inclined position face uppermost, with the head supported well above the water, and the invention is also applicable to that type of device described in United 20 States Patent No. 1028433.

A device according to the present invention comprises a waistcoat provided with a number of buoyant compartments around the body part, and provided with means 25 whereby the lower part may be contracted circumferentially to a suitable degree when desired. In addition to means whereby the lower part of the device may be so contracted one or more adjusting straps or like 30 adjusting devices may be provided at the back or at other suitable position or positions on the device.

The accompanying drawings illustrate by way of example one construction of device 45 according to the present invention.

Figure 1 is a front view of the device secured in position upon a wearer. Fig. 2 is a corresponding back view. Fig. 3 is a view of the inside of the device. Fig. 4 is a section X—X of Fig. 1.

Referring to the drawings, the body of the device is provided with three groups of buoyant compartments, two groups *a* and *b* disposed on each side of the front, and the 55 third group *c* disposed at the back. The

groups *a* and *b* may each consist of two as shown, or more compartments extending vertically from the waist line almost to the shoulder, and a third or additional compartment is disposed at the side of the device extending from the waist line to a point beneath the arm holes *d*. The back group of buoyant compartments *c* comprises two pairs of compartments the upper ends of which are substantially in alignment with the upper ends of the longer compartments disposed in the groups *a* and *b* and the lower ends of the compartments *c* are disposed at a point half way between the waist line and the lower part of the arm holes *d*. By arranging the bottoms of the rear compartments *c* above the waist line and above the level of the bottoms of the front compartments *a* and *b*, the greater buoyancy of the front of the waistcoat is assured and the person is supported in the water reclining backwardly. The upper ends of the buoyant compartments in the groups *a*, *b* and *c* are rounded as shown. Between the two pairs of compartments which compose the group *c* there is a tapering portion of the jacket *e* having its wider end at the bottom. The arm holes extend for some little distance above the tops of the buoyant compartments. The buoyant compartments are packed with a buoyant material such as kapok and preferably the amount of kapok packed into the groups *a* and *b*, taken together is greater than the amount packed into the group *c*. A reference to Fig. 4 will show how the buoyant compartments are constructed the kapok being entirely enclosed by the woven material of which the device is made, and the compartments bulging to an equal degree upon the inside and 85 the outside of the device.

In the construction shown in the drawings an adjusting strap *f* is shown having its ends secured respectively to those compartments of the group *c* which are disposed on either side of the part *e*.

Referring particularly to Fig. 3 it will be seen that the lower part of the device is provided with a tape, cord or the like *g* which may be secured to the inside of the device as shown at approximately its central point and which is adapted to run through loops *g*¹ disposed at suitable points around the lower part of the inside of the jacket. The two end loops *g*¹ are obliquely disposed 105 110

as shown in order to facilitate a downward turn being given to the ends of the tapes *g*. The device may be provided with pockets which may be externally disposed as shown at *h* Fig. 1, and which are preferably adapted to fasten at the top by button fastenings.

The device is adapted to be worn in the manner of a waistcoat as shown in Figs. 1 and 2 and it is provided with button fastenings *i* down the front, and a standard size of device may be used by persons of varying sizes by adjusting the strap *f* and the running cord or tape *g*, the latter serving in every case to prevent the device working up unpleasantly when in use, as it has a strong tendency to do, owing to the great buoyancy of the compartments *a*, *b* and *c*. The tape *g* also serves to relieve the pressure from under the arms of the wearer so that the buoyant effort of the device is applied to a considerable extent around the waist of the person leaving the upper part of him and particularly his arms, with greater freedom than is usual when wearing a life-saving device.

What we claim and desire to secure by Letters Patent is:—

1. A life saving appliance comprising a waistcoat provided with buoyant compartments at its back and at the two sides of its front, the compartments at the back being separated by a tapering portion extending to the bottom of the garment and being widest at its bottom end and provided with an adjusting device for contracting it, the bottoms of the back compartments being arranged above the waist line of the garment and above the bottoms of the front compartments to assure the greater buoyancy of the front of the garment.

2. A life saving appliance comprising a waistcoat provided with three groups of buoyant compartments one group disposed at each side of the front and another group disposed at the back, said back group being divided into two by a tapering portion having its wider end at the bottom an adjusting strap being disposed across said tapering portion, the front groups each comprising compartments which extend vertically

from the waist line almost to the shoulder, and the back group comprising a number of compartments which are disposed above the waist line, and means whereby the lower part of the device may be contracted circumferentially to a suitable degree when desired.

3. A life-saving appliance comprising a waistcoat provided with three groups of buoyant compartments one group disposed at each side of the front and another group disposed at the back, said back group being divided into two by a tapering portion having its wider end at the bottom an adjusting strap being disposed across said tapering portion, the front groups each comprising compartments which extend vertically from the waist line almost to the shoulder, and the back group comprising a number of compartments which are disposed above the waist line, provided with a flexible member running through loops disposed upon the lower portion of the device whereby the lower portion may be contracted circumferentially to a suitable degree when desired.

4. A life-saving appliance comprising a waistcoat provided with three groups of buoyant compartments containing kapok, one group disposed at each side of the front and another group disposed at the back, said back group being divided into two by a tapering portion having its wider end at the bottom an adjusting strap being disposed across said tapering portion, the front groups each comprising compartments which extend vertically from the waist line almost to the shoulder, and the back group comprising a number of compartments which are disposed above the waist line, provided with a flexible member running through loops disposed upon the lower portion of the device whereby the lower portion may be contracted circumferentially to a suitable degree when desired.

In testimony whereof we affix our signatures, in presence of two witnesses.

HECTOR MACFARLANE.
NORMAN EVERARD ROGERS.
